UNITED STATES PATENT OFFICE

2,605,756

UNIT FOR ADAPTING FIREARMS TO AIR
GUN OPERATION

Jacques Bertschinger, Wohlen, Switzerland

Application November 28, 1949, Serial No. 129,732
In Switzerland December 1, 1948

8 Claims. (Cl. 124—15)

1

My invention relates to apparatus for converting a firearm into an airgun, particularly to adapter apparatus that may be mounted in the breech of a rifle (such as a Swiss carbine, model 1931), to permit practicing with air-driven bullets.

To make practicing with a thus converted firearm actually useful for preserving one's marksmanship in cartridge firing, the following requirements must be met:

1. The aiming accuracy of the airgun at short distances and small targets must be equivalent to that of the firearm employed for greater distances and correspondingly larger targets.

2. The total weight of the airgun and its weight distribution must be similar to those of the firearm.

3. The pressure to be exerted by the trigger finger must be the same for the firearm and the airgun, and

Besides, the conversion of the firearm into an airgun and vice versa must be easily effected; and to keep the firearm always ready for action, it is also essential to prevent the weapon from being damaged due to its conversion or use as an airgun. Consequently, the following further requirements should also be satisfied:

4. It must be possible to convert the firearm into an airgun without removal of any parts with which only an expert is conversant.

5. The trigger mechanism, when the weapon is being used as an airgun, must not be subjected to pressure in excess of that employed when the weapon is used as a firearm, thus obviating abnormal wear.

6. The movable parts of the adapter must be insertable only where space for their movement is available, and the bore and cartridge magazine must be protected from being contacted by these movable parts.

It is an object of my invention to provide an adapter device that satisfies the foregoing requirements and is also relatively inexpensive to manufacture.

Another object of the invention is to make such an adapter device, or generally an airgun, less subject to detrimental effects or inadvertent release due to shocks acting on the weapon.

Still another object of the invention is to permit cocking an airgun, especially an airgun adapter unit inserted into the breech of a rifle, without requiring the very considerable change of position in which the known airguns, in contrast to firearms, must be held after firing before another shot can be fired.

2

The foregoing and more specific objects and advantages of the invention as well as the means for achieving them, these means being set forth with particularity in the claims annexed hereto, will be apparent from the following in conjunction with drawings which illustrate, by way of example, an adapter device according to the invention, mounted on a firearm to be controlled by the trigger of the firearm. The constituent parts of the adapter are shown in full lines whereas the parts of the fire arm proper are shown in broken lines. In the drawings:

Fig. 1 illustrates a vertical longitudinal section of the weapon cocked for firing;

Fig. 2 illustrates in plan view the spring-loading elements in cocked condition;

Fig. 3 is a side view of the same spring-loading elements also in cocked condition;

Fig. 4 is a horizontal longitudinal section and plan view of the spring-loading elements in released condition;

Fig. 5 illustrates a section on the line V—V of Fig. 4;

Fig. 6 illustrates, on a larger scale, a vertical longitudinal section of the latching device;

Fig. 7 illustrates the loading end of the weapon;

Fig. 8 is a plan view of the latching device with pertaining latch loops;

Fig. 9 shows the latching device viewed from above, without the latch loops;

Fig. 10 is a cross-section on the line X—X of Fig. 6 of the latching device; and

Fig. 11 illustrates a cross-section, on the line XI—XI of Fig. 6, of the latching device with the latch loops.

The main parts of the firearm are indicated by capital letters while the subsidiary parts are indicated by capital letters to which small letters are added.

40 The main parts of the inserted airgun adapter are indicated by numerals and the pertaining subsidiary parts are indicated by numerals to which small letters are added.

As illustrated, the adapter unit is inserted into the breech A of a rifle instead of the previously withdrawn breech bolt. The unit is latched in position by a catch 20a which is formed on a spring 20 and snaps over a shoulder Aa on the breech A (Figs. 1, 3).

45 The converted weapon is cocked by swinging a cocking lever 23 rearwardly as far as it will go (Fig. 2) and then returning it to the initial position (Fig. 4).

To load the weapon, a loading knob 15 (Fig. 55 1) is unscrewed. After inserting a bullet, the

barrel 3 is rendered air-tight by screwing knob 15 firmly against a packing disc 15a. A pin 15b of knob 15 then forces the bullet forwardly in front of air vents 3a. Thereafter the weapon is ready for firing.

More in detail, the adapter unit is designed as follows: The stationary structure of the unit has a pivot bracket 1a for the cocking lever 23 and is provided with a housing 16 for accommodating a portion of a spring-latching device to be released by the trigger slider C of the rifle (Figs. 1 to 4). Disposed within the cylinder tube 1 and firmly joined therewith is a closure cup 2 with a damping disc 2a (Figs. 1, 4, 6) which forms together with the tube 1 an air pressure chamber 1e. The rear end of chamber 1e is closed by a piston disc 6 with a sealing disc 7. Piston disc 6 is axially displaceable in cylinder tube 1 and firmly joined with a barrel 3 that extends axially through the cylinder tube 1 into a guiding tube 4 in which the barrel 3 is axially displaceable. Tube 4 is firmly secured to the front end of the cylinder tube 1 to form an extension thereof. The front portion of guiding tube 4 is inserted into the barrel of the rifle. The air barrel 3 has lateral apertures 3a (Figs. 1, 6, 8, 9) through which it communicates with the cylinder chamber 1e to supply the barrel 3 with compressed air when the unit is triggered. Firmly joined with the axially displaceable air barrel 3 is a latch sleeve 5 and a carrier 8. The piston spring 14 of the unit is disposed between the stationary closure cup 2 and the movable latching sleeve 5. When assembling the adapter unit, the air barrel is inserted from the rear through the cylinder closure cup 2 and screwed into the latching sleeve 5, after the piston spring 14 is placed in position.

The cocking device for compressing the piston spring 14 comprises three main elements, namely the above-mentioned cocking lever 23, a cocking slider 21, and an intermediate connecting link 22. The cocking lever 23 has a channel-shaped portion pivoted to lug 1a by a pivot pin 26. Lug 1a is firmly secured to the air cylinder 1 or an integral part thereof. Link 22 enters between the limbs of the channel portion of lever 23 and is pivoted thereto by a pin 25 to transmit the oscillating movement of cocking lever 23 through a pivot pin 24 to the slider 21 movable longitudinally in a guide Ab of the breech A (Figs. 2 to 5). The cocking elements are normally held in the initial position illustrated in Fig. 4 by the action of a spring Ba (Fig. 3) on a lock holder B and by the engagement of a lock holder tongue Bb (Fig. 5) with a recess 22a of link 22. A stop for limiting the cocking movement of the cocking lever 23 is provided by a recess 21b in slider 21 (Figs. 2, 4). Recess 21b is engageable with tongue Bb (Figs. 3, 4) on the lock holder B.

The latching sleeve 5 has an annular shoulder 5a (Figs. 1, 2, 4) in slidable engagement with the air cylinder 1. During the cocking movement, sleeve 5 is carried along by a nose 21a of slider 21 (Figs. 2, 4). Nose 21a projects through a slot 1c in the air cylinder 1. Nose 21a also engages a groove 5b (Fig. 2) in sleeve 5 to prevent the sleeve from turning.

A release pawl 16 is slidably mounted in the above-mentioned housing 1b of the stationary structure of the unit (Figs. 1, 6, 10) and is guided by that housing for movement toward the vertically movable trigger slider C of the

rifle, the latter being moved downwardly when the trigger proper is actuated. A spring 19, connected between a pin 17 of pawl 16 and a stationary pin 18 of housing 1b, tends to hold the pawl in the position shown in Fig. 6. In that position, the rear end of pawl 16 projects over the edge of the rear aperture 1d of the cylinder tube 1.

The latching device for the cocked piston spring comprises the above-mentioned carrier 8 which is screwed together with the barrel 3 behind the piston disc 6 (Figs. 1, 6, 7, 8, 9). A latching sleeve 9 is longitudinally movable on the carrier 8 and is under the pressure of a latch spring 10 (Figs. 1, 6). When the weapon is in released condition the latching sleeve 9 bears against the piston disc 6. The carrier 8 has a groove 8a on both sides (Fig. 9) in which are fitted two latch loops 13 (Fig. 11). When the unit is cocked, the air piston is latched by the loops 13 which then abut against a bevelled stop face 11a of a catch ring 11 (Figs. 6, 8, 9). The ring 11 is held in position by a closure cap 12 screwed onto the rear end of the cylinder tube 1. The outer diameter of sleeve 9 is approximately equal to the inner diameter of catch ring 11 so that the latch loops 13 cannot slide off the bevelled stop face 11a of the ring. The sleeve 9 is prevented from being moved forwardly by the pressure of spring 10 because the rear end of pawl 16 then abuts against an annular shoulder 9a of the sleeve. This latching engagement comes about during cocking of the unit as follows. As mentioned, the unit is cocked by moving the cocking lever 23 rearward to a stop and then returning it forward to its original position. During the first stroke, the cocking slider 21 is pulled to the rear and its nose 21a entrains the sleeve 5 so that the piston spring 14 is compressed. Together with sleeve 5, the barrel 3 with all its parts (6 to 10, 13, 15) is moved to the rear. During this movement the latch sleeve 9, biased by spring 10, at first abuts against the piston disc 6. When the shoulder 9a of sleeve 9 passes over the latching end of pawl 16, the pawl first yields downwardly and then catches in front of the shoulder 9a. Now the cocking lever has reached the stop and its return movement begins. The elements of the cocking device now return to the original position, and the pressure of the piston spring also causes the barrel 3 with its attached parts (5 to 8, 13, 15) to return to the normal position. However, the slideable pawl 16 then bears against the trigger slider C and arrests the latch sleeve 9 which, therefore, does not participate in the return movement. Consequently, the spring 10 between the relatively moving parts 8 and 9 is stressed, and the two tongues 9b of sleeve 9 (Figs. 6, 8, 9, 10) enter into the latch loops 13 and spread them outwardly by the wedging action of bevel faces 9c at the rear ends of the respective tongues. Thereafter, the latch loops 13 abut against the rear bevel face 11a of the catch ring 11, thus stopping the forward movement of the barrel 3 shortly before the cocking elements reach the normal position. The weapon can now be charged with a bullet as described previously and is then ready for firing.

When the trigger of the rifle is actuated, the slider C moves downwardly and releases the pawl 16. Forced by spring 10, the latch sleeve 9 and the pawl 16 now jump forward. The rear end of pawl 16 has a curved edge 16a (Fig. 6) sliding over the rear edge of the cylinder aperture

1d so that pawl 16 is deflected downwardly and becomes disengaged from the shoulder 9a. Simultaneously, the two latch loops 13 are released by the forward movement of the two bevel faces 9c. The force of the piston spring 14 now causes the two loops 13 to slide off the bevel faces 11a of the catch ring 11, and the piston spring 14 can now freely expand. The air compressed in the air cylinder chamber 1e passes through the openings 3a into the barrel 3 to drive the bullet.

The adapter unit can be separated from the rifle by a simple manipulation. The catch 20a (Fig. 3) is released and the unit withdrawn straight rearwardly as far as it will go. Then the lock holder B is pressed downwardly, whereupon the unit can be fully removed and the breech bolt of the rifle inserted.

An airgun unit or adapter according to the invention, as embodied in the above-described example, is extremely shakeproof, i. e. secures a safe latching of the cocked piston against inadvertent release by shocks. This advantage is obtained despite the fact that the strong force of the piston spring does not react upon the trigger and that very little triggering force, not more than required in a firearm, is sufficient to release the gun. Due to the fact that the cocking device is mounted laterally of the weapon and has an outwardly swinging cocking lever, the unit according to the invention has also the advantage that it can be cocked without necessity of then holding it in a position greatly different from the normal shooting position, thus obviating a marked disadvantage of the conventional air-guns.

While in the above-described embodiment the airgun barrel accompanies the movement of the air piston, such a joint movement is not absolutely necessary for realizing essential features of the invention. It will also be understood that certain features of the invention are not limited to adapter devices but may also be applied to airguns or pistols in general, without departing from the scope of the claims annexed hereto.

I claim as my invention:

1. An adapter device, insertable into the breech of a firearm with a downwardly movable trigger member, for converting the firearm into an airgun, comprising a barrel, a cylinder, a structure movable axially of said cylinder and having a piston in said cylinder to form therewith an air pressure chamber communicating with said barrel, a piston spring joined with said structure for moving it axially in the air compressing direction, a cocking device linked to said structure for moving it in opposition to said spring, latching means for latching said structure in the cocked position having a part movably mounted on said structure and biased toward unlatching of said structure, a latch control member displaceable parallel to said direction and having a pawl end and a stop end at its respective extremities, said pawl end being engageable with said latching part near the end of the cocking movement to place and hold said latching part in latching position relative to said structure, said stop end being engageable with the trigger member to be stopped thereby from displacement when said structure is cocked and latched, said cylinder having deflecting means engageable with said pawl end during said displacement to then deflect said pawl end away from said latching part, and spring means biasing said control member in the direction of said displacement

whereby said control member is displaced and released from said latching part when the trigger member is downwardly actuated away from said stop end.

- 5 2. An adapter device, insertable into the breech of a firearm with a downwardly movable trigger member, for converting the firearm into an airgun, comprising a barrel, a cylinder, a structure movable axially of said cylinder and having a piston in said cylinder to form therewith an air pressure chamber communicating with said barrel, a piston spring joined with said structure for moving it axially in the air compressing direction, a cocking device linked to said structure for moving it in opposition to said spring, latching means for latching said structure in the cocked position having a part movably mounted on said structure and biased toward unlatching of said structure, a latch control slider displaceable parallel to said direction and having a rear end engaging said latch part in the cocked position of said structure to then hold said part in latching position, said slider having a front end abutting against the trigger member in said cocked position and being thereby stopped from forward displacement, said cylinder having a part engageable with said slider rear end during forward displacement of said slider to deflect said slider rear end away from said part due to said forward displacement, and spring means biasing said slider toward forward displacement whereby said slider is displaced and released from said latching part when the trigger member is downwardly actuated away from said front end.
- 20 3. An airgun device, comprising a barrel, a cylinder, a structure movable axially of said cylinder and having a piston in said cylinder to form therewith an air pressure chamber communicating with said barrel, a piston spring joined with said structure for moving it axially in the air compressing direction, a cocking device linked to said structure for moving it in opposition to said spring, latching means for latching said structure in the cocked position having a part movably mounted on said structure and biased toward unlatching of said structure, a latch control slider displaceable parallel to said direction and having a rearward pawl end and a forward stop, said pawl end being engageable with said latching part near the end of the cocking movement to place and hold said latching part in latching position relative to said structure, a movable trigger member abutted by said stop when said structure is cocked to then prevent forward displacement of said slider, said slider having a curved portion and said cylinder having a part engageable with said portion during forward displacement of said slider to then deflect said slider away from said latching part, and spring means biasing said slider toward forward displacement whereby said slider is displaced and released from said latching part when said trigger member is moved away from said stop.
- 40 4. In a device according to claim 3, said latching means comprising a carrier forming part of said structure and being disposed coaxially of said piston, latching loops mounted on said carrier and being outwardly deflectable therefrom to latching position, and said movable part consisting essentially of a sleeve member axially displaceable on said carrier and wedgingly engageable with said loops to force them to said latching position when moved rearwardly of said car-

rier, a stationary catch ring joined with said cylinder in coaxial relation to said carrier and engaged by said loops when said structure is cocked and said loops are in said latching position.

5. In a device according to claim 4, said spring means for biasing said latch control slider being mounted on said structure and disposed between said carrier and said sleeve member, and said spring member having a biasing force axially directed to move said sleeve member forwardly relative to said carrier.

6. In a device according to claim 1, said latching means comprising a carrier firmly secured to said movable structure to form part thereof, latching elements mounted on said carrier and being deflectable radially away from said carrier to latching position, a stationary catch ring firmly joined with said cylinder in coaxial relation to said carrier and engaged by said latch elements in the cocked position of said structure to then latch said structure in the cocked position, said latching part being engageable with said elements for deflecting them to said latching position when engaged by said latch control 20 member. 25

7. In a device according to claim 1, said cocking device being mounted laterally of the device and having a laterally reciprocable cocking handle so as to be operable in the normal shooting position of the firearm.

8. An adapter device according to claim 1, comprising a snap-spring catch member mounted on the device and engageable with the firearm to fasten the inserted adapter device in the breech of the firearm.
